UNITED STATES PATENT OFFICE.

PATRICK H. McGRATH, OF WOLLASTON, MASSACHUSETTS, ASSIGNOR TO INTERTYPE CORPORATION, OF BROOKLYN, NEW YORK, A CORPORATION OF NEW YORK.

LINE AND SPACE INDICATING MECHANISM FOR TYPOGRAPHICAL MACHINES.

1,229,108.

Specification of Letters Patent.

Patented June 5, 1917.

Application filed November 25, 1914. Serial No. 873,876.

To all whom it may concern:

Be it known that I, PATRICK H. McGRATH, a citizen of the United States, residing at Wollaston, in the county of Norfolk and State of Massachusetts, have invented certain new and useful Improvements in Line and Space Indicating Mechanism for Typographical Machines, of which the following is a specification.

10 This invention relates to line and space indicating mechanism for typographical-machines, the object of the invention being to provide instrumentalities of a simple and effective character by which the operator of 15 such a machine can readily determine the state or condition of the line both with respect to the matrices, type or their equivalent and spaces. The line indicating means and the space indicating means may, however, in 20 some instances be used separately, although I prefer to employ them together.

In the drawings accompanying and forming part of the present specification I have shown in detail one of the several convenient forms of embodiment of the invention which to enable those skilled in the art to practice the same will be set forth fully in the following description. I do not limit myself to this particular disclosure; I may 25 de- 30 part therefrom in several respects within the scope of the invention defined by the claims following said description.

Referring to said drawings:

Figure 1 is a perspective view of a typographical-machine of one kind, equipped with line and space indicating mechanism involving my invention.

Fig. 2 is a front elevation partially in section, of the principal parts of the line indicating and space indicating mechanism and an inclosing case therefor, with part of a power transmitting shaft.

Figs. 3 and 4 are cross sections on the lines 3-3 and 4-4 respectively of Fig. 2, looking in the direction of the arrows.

Fig. 5 is a front elevation of one end of the casing, showing the two movable indicating elements, the face-plate being removed.

Fig. 6 is an end elevation partly in section 50 on the line 6-6 of Fig. 2.

Fig. 7 is a view of the upper end of said shaft, a pinion and a rack, and certain co-operating devices hereinafter more fully described.

Like characters refer to like parts throughout the several views which it will be noted are on different scales.

In Letters Patent No. 1,118,298 granted to me November 24, 1914, for a line-indicating mechanism for typographical machines, 60 is shown a line-indicating element operative with the assembler-slide of such a typographical machine. As will be inferred the present machine comprises a movable line-indicating element and while as will herein-after appear, this line-indicating element is movable between the keyboard or between the space bar and the copy carrier or pan, this is not always necessary. As intimated there is a space-indicating element and while 70 this space-indicating element may be located in any desirable place, I prefer that it be between the space-bar and the copy-carrier, in that the field to be covered by the operator in setting matrices, type or their equivalents 75 and spaces is of the smallest compass. The line-indicating element so far as its general character and mode of operation are concerned, is practically the same as in the Letters Patent mentioned. The space indicator, 80 however, is actuated with or by the space bar or analogous member. Broadly, therefore, one of the features of the invention is a space indicating element operative in some suitable manner with its space bar. There 85 are in fact many fundamental points of novelty, as will more particularly appear in my claims. In the construction shown and hereinafter described, the purpose of the space-indicating element is to show the expansive 90 possibilities of a line. This space-indicating element is advanced each time the space-bar is operated, each step of the space-indicating element being equal to the maximum expansion of a space, by virtue of which the operator 95 can determine by glancing at the said space-indicating element, the expansive possibilities of a line.

With the foregoing general observation it is now proper to refer more in detail to the 100 drawings. In Fig. 1 I have shown parts of a typographical machine such as that employed for setting matrices. This machine comprises a keyboard as 2, a space bar or key as 3, a copy carrier, pan or tray as 4 and an 105 assembler slide as 6.

As already observed the two indicating elements may be located in any convenient

place, but the best results as will be gathered, are obtained by positioning them between the space bar 3 and the copy pan 4. The indicating elements and certain coöperative devices are preferably mounted in a suitable casing as 7 which as shown is of practically V-form in cross section and which may have fastened to it, brackets as 8' to be attached by screws or otherwise, to the frame of the machine, in the interval 10 between the space-bar 3 and copy-pan 4. The front of the casing 7 consists of plates 8, 9 and 10, the plates 8 and 9 being removably held in place by screws or otherwise 15 and the plate or cover piece 10 having a lower stationary section also held in place by screws, and an upper swinging section, which upper section can be swung back to obtain access to the interior of the casing 20 for a purpose that will hereinafter appear. In the cover-piece 8 is a longitudinal slot 11 through which the line-indicating element hereinafter more particularly described can be seen, said slot or sight opening 11 being 25 intersected at one end thereof, by the slot or second sight opening 12 through which the space-indicating element can be read. The line-indicating element is denoted by 13 and the space indicating element by 14, 30 the line-indicating element being adapted to traverse in a practically straight line the field or background or fixed indicating portion 15 while the space-indicating element traverses the field or fixed indicating portion 16. To facilitate reading of the two 35 indicating elements the fields may be white and the indicating elements black, although this is a detail. As will hereinafter appear the two indicating elements move step by 40 step in opposite directions, the advancing movement of the indicating element 13 being toward the left in Figs. 2 and 5, while the advancing movement of the indicating element 14 is toward the right in said two views. 45 The line-indicating element 13 may be operated in any desirable manner, although the means shown for this purpose and now to be described are satisfactory. Said line indicator 13 as shown consists of an upward 50 projection or pointer fastened suitably to the forward end of the rod 16 connected in some convenient manner to the forward end of the rack 17, the rod 16 inclosed by the casing 7 constituting practically a plain 55 continuation of the rack which projects through an opening in one closed wall of said casing and is slidably mounted in the channeled guide member 18 rigid with said wall, said guide member having duplicate 60 forwardly extending lugs 19 perforated to receive the shaft 20 to which is pinned or otherwise suitably fixed the pinion 21 in mesh with the teeth of the rack 17, the consequence being that when the shaft 20 is 65 turned, the line-indicating element 13

through the described parts will be operated. The upper of the two lugs 19 has a boss 22 which fits in the bearing sleeve or tube 23, there being a threaded engagement as shown, between the boss and the tube, the shaft 20 being inclosed jointly by the tube and boss all as illustrated best in Fig. 6. Threaded into the upper end of the tube 23 is the depending boss 24 of the tubular guide member 25 cut away or slotted to receive the pinion 26 which meshes with the rack 27, the tubular guide member 25 being rigid with the bracket 28 fastened by screws or otherwise, to the framework of the machine. The pinion 26 is loose on the shaft 20, although normally it is rigidly connected therewith so as to rotate with said shaft. The means shown for rigidly connecting the pinion with the shaft will be hereinafter described. When the pinion 26 is rigid with said shaft 20, it follows that on the turning of said pinion by the rack 27, the shaft 20 and consequently the pinion 21 will be also rotated to effect the motion of the line-indicating element 13 in the manner described. The rack 27 is connected at its forward or inner end with the bracket 29 which in turn is connected with the assembler-slide 6. Normally therefore, when the assembler-slide 6 moves the line-indicating element 13 acts in unison therewith through the intermediate mechanism set forth. The advancing movement of the assembler-slide 6 in the construction shown is in the same direction as that of the line-indicating element 13. It will be assumed that both of them are in their primary positions. On the introduction of a matrix or type into the line, the assembler slide 6 is advanced one step, a corresponding movement naturally occurring with respect to the line-indicating element 13, by reason of the connections therebetween. As will be understood the line-indicating element may be of a radically different character. It is not essential that mechanism such as that alluded to need be interposed between the two parts for effecting the operation of the line-indicating element by or through the action of the assembler slide. 110

In typographical-machines involving an assembler-slide the length of line varies, and I provide means for adjusting the relation between the assembler-slide and the line-indicating element 13, so that the two parts 120 may have approximately the same amount of travel. The power-transferring connections between the assembler-slide 6 and the line-indicating elements 13 or their equivalents, are adjustable in character, so that the initial setting or positioning of said element 13 may be made to conform with that of the assembler-slide and the loose pinion 26 to which I have already referred plays in the construction shown, a part in this particu- 130

lar independent relative adjustment of the assembler slide and line indicating element. The shaft 20 has a stop or abutment thereon, the collar 30 answering satisfactorily in this respect, the thumb-nut 31 threaded onto said shaft presenting a convenient means for normally pressing the pinion 26 against the collar, so that under operating conditions the shaft 20 and pinion rotate as one, the pinion as will be understood being disposed between the collar and nut. The shaft 20 at its upper end is provided with the operating thumb-piece 32. When the length of line has been determined, the nut 31 will be backed away from the pinion 26 so that the shaft 20 can run free in the pinion. This permits the independent movement or adjustment of the line-indicating element 13 and assembler slide 6, the adjustment of the line-indicating element 13 being accomplished by the rotation of the shaft 20 through the operating member 32, while the assembler slide 6 can be directly adjusted. When the necessary relative adjustments are obtained the nut 31 will be manipulated to clamp the pinion 26 against the collar 30.

The space-indicating element 14 has a somewhat elongated shank 33 fastened suitably to the rack 34, the coiled pull spring 35 being connected to the outer end of the rack 34 and also to the outer closed wall of the casing 7, the tendency of the spring 35 being constantly to advance the rack 34 and consequently the shank 33 and space indicating element 14, this motion, however, being resisted by a suitable mechanism such as that shown and now to be described. Mounted for oscillation in the casing 7 at approximately the junction of its branches is a three-armed escapement member consisting of the rigidly-connected arms 36, 37 and 38, the arm 38 projecting through a slot 39 in the cover member and its free end being coöperative with the cam or tappet 40 fastened rigidly in some suitable manner to the body of the space bar 3. The arms 36, and 37 are provided with teeth 41 and 42 coöperative with the teeth of the rack 34, the teeth 41 and 42 being of "spring" type and bent in such manner and as shown in Fig. 2 to check or cause the intermittent advancing movement of the rack 34 under the action of the spring 35 but to freely permit return movement of said rack. On each downward movement of the space bar 3 which occurs on the introduction of a space into the line, the cam, actuator or tappet 40 will strike the arm 38 and swing the same to the left in Fig. 2, thus raising the tooth 41 clear of the rack 34 and moving the tooth 42 downwardly into engagement with the rack teeth by reason of which the rack 34 in the interval, can be advanced one step or a distance equaling the width of one tooth 65 thereof on each intermittent movement of

the space bar 3, the amount of movement of the rack 34 and hence of the space-indicating element 14 agreeing with the length of the maximum expansion of a line.

The line-indicating element 13 is advanced 70 with the assembler slide 6 and is retracted therewith also. The intermittent advance of the space indicating element 14, however, is caused as will be understood by the space bar 3. Retractive movement of the space 75 indicating element 14 is directly accomplished by the line-indicating element 13 or parts associated therewith. As a matter of fact the assembler slide 6 is the primary agent for effecting the return movement of 80 the part 14, the necessary power for this action being derived from the assembler-slide which acts in the construction shown, through the line-indicating mechanism. The means shown for accomplishing the action 85 in question will now be set forth.

The rack 34 meshes with the pinion 45 rotatively mounted in the casing 7 and meshing in turn with the rack 46 provided with projections 47 and 48 connected by the 90 rod 49 on which is adjustably mounted the collar or block 50 having a spring-actuated tooth 51 adapted to enter any one of the spaces between the teeth of the rack 46. By disengaging the tooth 51 from the rack 46 95 the block or collar 50 can be slid along the rod to adjust the same to conform to the particular position of the line-indicator 13 and assembler slide 6 and when the adjustment is obtained, the tooth 51 will be released and will enter the appropriate tooth space of the rack 46 to maintain said adjustment. On the advance of the indicating element 14 in the manner set forth the rack 34 moves to the right, the rack 46 through 100 the intermediate pinion 45, being moved toward the left, it being understood that the collar or block 50 moves with the rack 46, this movement of the two racks occurring simultaneously. The collar or block 50 is 105 engaged by the restoring element 52, consisting as shown of a projection on the rod 16 when the parts are being returned to their initial positions. It therefore, follows that as the indicating element 13 is 110 returned to its primary position, the rod 16 at this time moving to the right, the rigid projection 52 on said rod, by engaging the collar or block 50 moves the rack 46 in a corresponding direction, thereby rotating 115 the pinion 45 to impart a movement toward the left of the rack 34 and necessarily a retractive or return movement to the space indicator 14, the motion in question continuing until the two indicating elements reach 120 their initial positions. When the indicating element 14 is in its primary position its forward or outer edge will be in register virtually with the background or field 16, as shown practically in Fig. 1. On the move- 125

ment of the indicator toward the right in Fig. 5 this field or background will be uncovered, the length of background between the outer edge thereof and the outer edge of 5 the indicator 14 showing in a simple way the expansive possibilities of the spaces which are in the line so that the operator by glancing at the indicator 14 and its field if necessary, but usually merely at said indicator, can tell just what can be secured in 10 the way of expansion. The extreme forward end 53 of the indicating field 16 might be considered the zero line of the space indicating means, the space indicating means 15 being made up of the field, or fixed indicating portion 16 and the movable indicating element 14. There is provided for the rack 46 a stop such as that denoted by 48', the projection 48 of said rack being adapted 20 to engage said stop when the rack reaches its initial position as shown in Fig. 2.

What I claim is:

1. The combination with the matrix assembler mechanism and the space mechanism of a typographical machine of the linotype class, of indicators operative respectively by the assembler and space mechanisms and coöperative with one another to indicate directly the length of a line of selected matrices and expanded spacers. 25

2. The combination with the assembler-slide of a typographical-machine, an indicating element, a rotary shaft operatively connected with said indicating element, a pinion loose on said shaft, a rack connected 35 with the assembler-slide and in mesh with said pinion, and means for rigidly connecting said pinion with said shaft.

3. The combination with the assembler-slide and the space-bar of a typographical machine, of two independently movable indicating elements, means actuated by the assembler-slide, for operating one of said elements, and means actuated by the space-bar, for actuating the other indicating element. 45

4. The combination with the assembler-slide, the space-bar and the copy-carrier of a typographical-machine, of two independently movable indicating elements located 50 between the space bar and the copy carrier, means actuated by the assembler-slide, for operating one of said indicating elements, and means actuated by the space-bar, for actuating the other indicating element.

5. The combination with the assembler-slide, the space-bar and the copy-carrier of a typographical machine, of two independently movable indicating elements mounted 55 between the space-bar and the copy-carrier, for movement approximately in parallelism with the space-bar, means actuated by the assembler-slide for operating one of said indicating elements, and means actuated by the space-bar for operating the other indicating element. 60

6. The combination with the assembler-slide and the space-bar of a typographical-machine, of indicating elements independently advancable in opposite directions, means actuated by the assembler-slide for 70 advancing one of said indicating elements, and means actuated by the space-bar, for advancing the other of said elements.

7. The combination with the assembler-slide, and the space-bar of a typographical-machine, of separately movable indicating elements, means operative with the assembler-slide on the advance thereof, for advancing one of said indicating elements, means operative with the space-bar for advancing the other indicating element, and means operative with the assembler-slide on the retraction thereof, for retracting both the indicating elements. 75

8. The combination with the assembler-slide, and the space bar of a typographical machine, of an indicating element, means operative with the assembler-slide for advancing and retracting said indicating element, a second indicating element, means 90 operative with the space-bar for advancing said second indicating element, and means operative with the first indicating element on the retraction thereof, for retracting said second indicating element. 95

9. The combination with the assembler slide and the space bar of a typographical machine, of indicating mechanism operative jointly by the assembler slide and the space bar and adapted to indicate the growth of 100 a line and the increase of its length to be produced by the expansion of the spaces therein.

10. The combination with the assembler mechanism and the space mechanism of a typographical machine, of indicating mechanism operative automatically on the action 105 of the assembler and the space mechanisms to indicate the growth of a line as determined by the cumulative thicknesses of the 110 matrices in the line and the increase of its length to be produced by the expansion of the spaces therein.

11. The combination with the matrix assembler mechanism and the space mechanism of a typographical machine, of a pair 115 of indicators movable in reverse directions by the assembler and space mechanisms and coöperative with one another to directly indicate the length of a line of selected 120 matrices and expanded spacers.

12. The combination with the assembler mechanism and the space mechanism of a typographical machine, of an indicator movable in one direction by the action of the 125 assembler mechanism, and an adjacent co-operative indicator movable in an opposite direction by the action of the space mechanism as determined by the expansive capacity of the spacers in a line, said indi- 130

cators having portions which coöperate to indicate directly when the selected line of matrices and expanded spacers will produce a line of predetermined length.

5 13. The combination with a typographical machine having an assembling slide for matrices and space mechanism for expandable spacers, of an indicator embodying two indicating members controlled respectively 10 by the assembling slide and the space mechanism, whereby the maximum and minimum allowable shortage may be ascertained.

14. The combination in a typographical machine using expandible spacers, of a line 15 indicator, and means for controlling the

same, said indicator embodying a member for indicating the actual shortage of the line, and a member for indicating the expandible capacity of the spacers in the line, the relative positions of the two members 20 adapted to indicate the maximum shortage which can be taken up by the expansion of the spacers.

In testimony whereof I affix my signature in presence of two witnesses.

PATRICK H. McGRATH.
